UNITED STATES PATENT OFFICE

DAVID H. ZELL, OF BROOKLYN, NEW YORK

DESIGN FOR A VANITY CASE OR ANALOGOUS ARTICLE

Application filed July 23, 1930. Serial No. 38,448. Term of patent 3½ years.

To all whom it may concern:

Be it known that I, DAVID H. ZELL, a citizen of the United States, residing at Brooklyn, in the county of Kings and State of New York, have invented a new, original, and ornamental Design for a Vanity Case or Analogous Article, of which the following is a specification, reference being had to the accompanying drawing, forming part thereof.

Figure 1 is a front elevation of a vanity case showing my new design;

Fig. 2 is an elevation of one longitudinal edge of the case;

Fig. 3 is a similar view of the opposite longitudinal edge of the case, and

Fig. 4 is an end elevation.

The dominant feature of the design resides solely in the ornamental form of the metal cap pieces at the opposite ends of the case body.

I claim:

The ornamental design for a vanity case or analogous article, as shown and described.

DAVID H. ZELL.
